8327X

The schedule referred to in these Spellers Patent and
making part of the same containing a description
in the words of the said Gideon Hatchells, of himself of
his improvement in the construction of the Threshing
Machine. To all persons to whom these Presents
shall come. Be it known that Gideon Hatchells
of the Town of Windsor in the County of Broome and
State of New York have invented a new and useful
improvement in the Threshing Machine used for separ-
ating wheat, barley, rye, oats, millet, buck wheat and
other small grain from the haulm or straw, and that
the following is a full and exact description of the ex-
clusive and operative parts of said machine as invented
or improved by him. This machine is placed upon
a frame of suitable dimensions and is composed of wood
or dark iron or part of wood and the other part of iron.

The full-piece is so constructed as to consist of a part of a circle and is usually made of wood and plated with silver, or otherwise of cast silver or other metal, and whether made of wood or silver plated with silver or cast silver, in either case said full piece is to be so constructed as to consist of concavities and convexities, and to present an uneven surface. The upper may be placed level or slanting, the grain is placed on this and impaled into the backside, and may pass between rollers or not; the moving parts of this backside consist of an even style or shape of suitable length and dimensions, and one end of which is placed a thimble or button to receive a stop or have it with convenient fastenings to the backside, also an even shape or style of fence box or some kind of case or other metal of suitable thickness and with a number of holes in each being

To these heads the beates are connected by thin rods or bolts, in such a manner as to turn so said rods or bolts in view of the sides and thereby striking as more possible blow on the hair or straw, than they could do provided they were permanently fixed on a drum, and at the same time if necessary yielding to any hard substance that may be contained in said straw or straw, said beates may be composed of iron or otherwise of part iron and part wood, said beates are constructed of sufficient dimensions to admit of a number of holes in each and where the rods or bolts pass through the same and thereby pass the means of being easily removed so as to suit anything of grain whether the straw requires more or little beating to separate the same from the straw need also to increase and diminish the diameter of said beates, said beates if constructed of iron ought to be of sufficient length to project weight or gravity sufficient to strike a blow hard enough to separate the grain from the straw, one side or edge of said beate is left straight and the other side or edge of the same is crooked or bent into teeth or otherwise crooked and also cut, the parts to which they are joined as originally areثبت in the construction of the frame, the same being of sufficient dimensions to receive the shaft or angle, and if constructed mostly of cast metal, made with loops or grooves so as to receive the legs to support the same, at a convenient height, and also with places in view of bayes for the angle shaft to turn on, and also like places for feeding salt etc. if used, and also with loops or grooves to receive the upper and lower or top of the same, and also for having the tail or head piece attached to the same, this being more durable less expensive and more permanent than

perity, either clews, and placed on land away, and not wanted for use, then the usual mode of making them, is this: secondly, the bed piece of the same whether the same be of cast metal or wood and plated with iron, may be grained or formed of hollow and round or concavities and convexities in such a manner as to form concave surfaces, and yet form a part of a circle in such a way as to form a proper curve for the roller or beater to lie in, and prevent the straw from escaping before it is thoroughly threshed. Those uneven surfaces in the bed piece may lay parallel to the shaft or axle or they may be circular, or they may be angular or else they may be placed in a position not parallel with the shaft or axle. The presenting these uneven surfaces in the bed piece, adds greatly to facilitate the separating the grain from the straw and is preferable to spikes or any other way now in use. Thirdly, the threshing beater, if constructed of iron or else of iron and wood, if of iron the same being formed of one piece, and so constructed as that whilst one part strikes the straw the other part being suspended or cut into teeth or bars may more perfectly separate the grain from the straw and is preferable to those beaters in which are placed spikes or nails, they being subject to become loose and some times to come out and thereby to injure the machine and damage the tools of those persons who may be near them, and also by having a number of holes in the ends of the beaters for the ends of bars to pass through, so that to stop them may thereby with little trouble, be placed in a great variety of positions, so as better to promote the desired operations on different kinds of grain and to add to or diminish the size of the roller as may be wanted. Merely, suggesting that it would be a good way of grain and

greatly adding to the performance of separating the grain from the straw in a short space of time. Also the heads being formed with a number of holes in each for threads or bolts to pass through greatly adds to the convenience of adjusting the heads to different kinds of grain.
